UNITED STATES PATENT OFFICE.

JOHN AUSTIN BEST, OF AUGUSTA, GEORGIA.

INDEX-BOOK.

SPECIFICATION forming part of Letters Patent No. 738,599, dated September 8, 1903.

Application filed April 17, 1903. Serial No. 153,067. (No model.)

To all whom it may concern:

Be it known that I, JOHN AUSTIN BEST, of Augusta, in the county of Richmond and State of Georgia, have invented a new and useful 5 Improvement in Index-Books, of which the following is a specification.

My invention is in the nature of a novel index-book by which the overflow of names from the alphabetic divisions allotted to them 10 may be conveniently located and classified and accurately and quickly referred to and by which also the number of pages of an index may be greatly reduced without lessening the 15 number of names to be indexed, securing the largest possible classification of names within an index of minimum size.

My invention consists in the novel construction and arrangement of the parts of the index, as hereinafter fully described with reference 20 to the drawings, in which—

Figure 1 represents two adjacent pages of my index opened for the initial letter "S" and with names entered for the first vowel "A" and with the reference at the bottom of 25 the column to the supplementary number-divisions of the index which are to contain the overflow. Fig. 2 is a similar view of the index opened at the division-number indicated at the bottom of the column of names in Fig. 30 1 and showing the groupings of the overflow names. Fig. 3 is a view of the complete index as arranged along the right-hand side of the book, the book being opened at the first page. Figs. 4, 5, 6, 7, and 8 are views of 35 modifications.

Referring to Fig. 3, my index in its preferred form has two parallel rows of reference characters on the right-hand side of the page—one of initial letters, as seen at *a*, and 40 the other of numerals, as seen at *b*. They are formed by the cutting-in process, leaving overlapping flaps rising from the bottom upward. The lettered series *a* extends from the top of the page to the bottom, and the numbered series *b* also extends from the top to the bottom. 45 The lettered series *a* has one initial letter for two or more pages, as seen at *S* in Fig. 1, and these pages are preferably, but not necessarily, divided into vertical vowel-columns "A," "E," "I," "O," "U," "Y," for the subdivision and classification of the names by first vowels, and at the bottom of each column, as

shown, or at some other suitable point on the page there is the overflow-reference to a number-subdivision of *b* by the words "Extended 55 under Division No. —."

In the present instance the division-number of series *b* under which the overflow is classified is 25. A turn to this subdivision exposes the pages seen in Fig. 2, where the 60 overflow of the names of the initial "S" and first vowel "A" are seen under the division 25. The pages for these number-subdivisions are divided into any number of subdivisions for each page, (six, as seen in Fig. 2,) and the 65 index-numbers for this series *b* are therefore grouped in twelve numbers, "25" to "36," inclusive, so as to cover both pages, as exposed by one opening of the book.

In Figs. 1, 2, 3 both the alphabetical index 70 *a* and numerical division-index *b* are coextensive with the length of the page and are arranged parallel to each other in two columns side by side; but they may as well be arranged in a single column, as seen in Fig. 75 4, with the alphabetical index *a'* at the top and the numerical division-index *b'* at the bottom forming a continuation of the same column. Furthermore, instead of locating the two indexes on the exposed overlapping 80 edges of cut-in leaves, as in Figs. 1, 2, 3, I may apply the index by separately-formed tabs *a*² *b*², pasted onto the edge of the leaves, as in Fig. 5, either in two parallel series, after the arrangement shown in Fig. 3, or in a single column, as shown in Fig. 6, after the arrangement shown in Fig. 4.

As a further modification I may, as in Fig. 7, locate the second column of index-numerals in an inseparable series on the protruding edge of the inside of the book-cover or blank leaf, as at *b*³, allowing the separable thumb-pieces *b*⁴ to remain blank and serving in such case only the mechanical value of selective action in opening the book at the 95 proper page, (indicated by the figures seen at *b*³.)

As shown, the bottom of each name-column of the alphabetical index bears the printed reference-note "Extended under Division 100 No. —;" but it is obvious that this may be replaced by any written note of the book-keeper—such as "see No. —," &c.—it being only necessary to my invention that there

should be a reference-space at or near the end of the name-spaces for this purpose. After the overflow of names fills one of the spaces allotted to it in the numerical index-division reference is to be made in said division to a second numerical division for the second overflow, as shown in Fig. 8.

Having thus described my invention, what I claim as new, and desire to secure by Letters 10 Patent, is—

1. An index-book having an alphabetical index on one set of pages, and a numerical index on another set of pages, both indexes being exposed along the edges of the pages, the 15 pages of the alphabetical index being divided into name-columns having spaces appropriately designated to receive a reference to the numerical index for the overflow of names, and the pages of the numerical index having 20 numbered subdivisions to receive such overflow of names, said subdivisions being numbered to correspond to the numbers of the numerical index exposed at the margin substantially as and for the purpose described.
2. An index-book having an alphabetical index on one set of pages and a numerical index on another set of pages, both indexes being exposed along the edges of the pages, the pages of the alphabetical index being di- 25 30 vided into name-columns having each a se- parate vowel letter and also reference-spaces appropriately designated to refer to the numerical index for the overflow of names, and the pages of the numerical index having num- 35 bered subdivisions, the numbers of said sub- divisions corresponding to the numbers of the numerical index exposed at the margin substantially as and for the purpose de- scribed.

3. An index-book having an alphabetical 40 index on one set of pages extending along its side margin from the top to the bottom of the page and extending through the first portion of the pages of the book, said pages being divided vertically into name-columns with 45 spaces appropriately designated for reference to a numerical index to receive the overflow, said numerical index being on another set of pages and also extending from the top to the bottom of the book in a vertical column parallel to the column of the alphabetical index and beside the same, the pages of the numerical index being in the latter part of the book and subdivided into numbered spaces, corresponding to the numbers of the exposed 50 55 part of the numerical index, to receive the overflow substantially as and for the purpose described.

4. An index-book comprising three sets of 60 pages; one set having an alphabetical index at the margin and being subdivided into vertical name-columns with each column appropriately designated to refer to a numerical index, the other set of pages being divided into numbered overflow-subdivisions and having a vertical series of blank finger-tabs along their margins, and another page bearing an inseparable or unbroken numerical index arranged vertically and parallel to the series of blank finger-tabs, the unbroken numerical index having its numbers set opposite to the finger-tabs which they indicate substantially as described.

JOHN AUSTIN BEST.
